UNITED STATES PATENT OFFICE.

JOHN GEORGE HAUS, OF WEIRTON, WEST VIRGINIA.

WATER HEATER.

Application filed April 22, 1924. Serial No. 715,258.

To all whom it may concern:

Be it known that I, JOHN G. HAUS, a citizen of the United States, and a resident of Weirton, in the county of Hancock and State of West Virginia, have invented a new and Improved Water Heater, of which the following is a full, clear, and exact description.

This invention relates to water heaters and more particularly to water heaters for domestic uses, although, of course, the invention is not limited to the particular use, an object of the invention being to provide a water heater which may be connected to a domestic boiler by tank and which will quickly and economically heat the water in the boiler or tank.

A further object is to provide an improved construction of heating unit especially designed for use in connection with a gas burner, which unit insures a circulation of the water in a relatively small stream so that in its passage through the unit it is heated to a high degree and returned to the boiler from whence it came in a highly heated condition.

A further object is to provide a water heater which may be readily installed in connection with ordinary domestic boilers, which will result in an economy of space and which will most efficiently perform the functions for which it is intended.

With these and other objects in view, the invention consists in certain novel features of construction and combinations and arrangements of parts which will be more fully hereinafter described and pointed out in the claim.

In the accompanying drawings—

Figure 1 is a view, mainly in longitudinal section but partly in elevation, illustrating my improved water heater in connection with an ordinary domestic boiler;

Figure 2 is an enlarged view in transverse section on the line 2—2 of Figure 1;

Figure 3 is a similar view in section on the line 3—3 of Figure 1;

Figure 4 is a view in transverse or horizontal section through the water heating unit, the view being taken on the line 4—4 of Figure 5;

Figure 5 is an enlarged view in vertical section through the lower portion of the boiler and the heating unit;

Figure 6 is a fragmentary detailed view illustrating the manner of connecting the heating unit to a boiler support.

1 represents a boiler, 2 an inlet pipe which projects to a point adjacent the bottom of the boiler for supplying cold water thereto, 60 and 3 is an outlet pipe for carrying off hot water from the boiler.

The boiler 1 is supported upon suitable legs or feet 4, and my improved heating unit 5 is located directly under the boiler 1 and 65 is provided with any desired number of perforated lugs 6 to receive bolts 7 projected through slots 8 in the feet or legs 4 to permit of a certain amount of adjustment to properly position the heating unit 70 with relation to the boiler. Some provision for adjustment is desirable as domestic boilers may be provided with flat bottoms, concave bottoms or convex bottoms, and hence to properly locate the unit provision 75 must be made for adjustment thereof relative to the feet or legs of the boiler.

The heating unit 5 is preferably of cylindrical form and at its upper end is made with a sleeve 9 which has screw-threaded 80 engagement, as shown at 10, with a nipple 11 constituting an outlet for the bottom of the boiler 1. At the top or the upper portion of the heating unit 5 I provide a heating chamber 12 in which a vertical partition 13 is located forming the chamber 12 into a relatively long circuitous passage, the inlet 14 of which is located at the periphery of the chamber and is connected by a passage 15 with the nipple 11 of the boiler 1. 90

The outlet of said chamber 12 which is at the center thereof communicates with a vertical tube 16, preferably screwed into a threaded nipple 17 at the center of the chamber 12. This tube 17 is appreciably smaller 95 than the nipple 11, is projected centrally therethrough, and extends up into the boiler 1 the desired distance so that the hot water is discharged into the top or upper portion of the boiler 1. To prevent this water from being chilled a tubular casing 18 is provided around the tube 16 and preferably filled with material 19 which will prevent heat radiation.

The heating unit 5 below the water heating chamber 12 is made with a depending apron 20 in which a suitable burner 21 is located for heating the chamber 12, and this

apron 20 is made with outlets 22 in its wall to allow for the necessary draft and to permit the heating units to pass upwardly and around the heater and against the bottom of the boiler to assist in raising the temperature of the water. This burner 21 preferably constitutes a gas burner although, of course, it is to be understood that the invention is not limited to the particular type of burner or to the fuel employed as it is obvious that oil, electricity or other heating means may be employed.

A drain cock 23 communicates with the inlet 14 of chamber 12 so as to drain off the water from the heating unit and from the boiler as well whenever occasion may require.

In operation, cold water from the boiler 1 flows downwardly through nipple 11, passage 15 into inlet 14 and thence travels in a circuitous path through the chamber 12 where it is subjected to the intense heat of the burner 21. The water after its passage through the chamber 12 enters pipe 16 and

is discharged into the upper portion of the 25 boiler 1.

While I have illustrated what I believe to be a preferred embodiment of my invention it is obvious that various slight changes and alterations as fairly fall within the 30 spirit and scope of the appended claim may be made.

I claim:

A water heater, comprising upper and lower plates, a partition connecting said plates and forming a thin circuitous water chamber or passage having its inlet and outlet at its outer and central portions, said heater having a depending apron perforated adjacent the lower plate of the heater 40 and adapted to receive a burner confined within the apron, said perforations constituting an outlet for air admitted through the bottom of the open apron, lugs projecting radially from the apron, and means for 45 adjustably securing said lugs to the legs of a boiler.

JOHN GEORGE HAUS.
